UNITED STATES PATENT OFFICE.

ROBERT E. McCREARY, OF GUNTERSVILLE, ALABAMA.

CLOTHES-PIN.

946,255.

Specification of Letters Patent. Patented Jan. 11, 1910.

Application filed April 21, 1909. Serial No. 491,231.

To all whom it may concern:

Be it known that I, ROBERT E. McCREARY, a citizen of the United States, residing at Guntersville, in the county of Marshall and 5 State of Alabama, have invented a new and useful Clothes-Pin, of which the following is a specification.

My invention relates to clothes pins, and has for its object to provide a device of this 10 character which can be kept permanently on the clothes line and can readily be carried to any point on the clothes line, whereby to secure a handkerchief or a blanket with equal effectiveness.

Another object is to provide a device of this character that can be used on metal 15 clothes lines so that the articles secured will not come in direct contact with the line, and thus will not be soiled by the rust on the line.

Still another object is to provide a device of this character that will adjust itself to every strain put upon it and will retain articles of different sizes, and hold them securely in the strongest breeze.

With these and other objects in view, which will be shown in the following specification, and set forth in the claims, my invention embraces the structure illustrated in the accompanying drawing, wherein:

Figure 1 is a perspective view of the clothes pin in applied position. Fig. 2 is an enlarged detail, with a portion cut away to show the method of securing the pin to the clothes line.

It is a well known fact that with the usual style of clothes pin, difficulty is experienced in securing the articles to the line so that when a strong breeze is blowing, the articles will not twist about and work out of the 35 pin. Every housekeeper knows that it is almost impossible to secure heavy articles to a metal line by the usual form of clothes pin, and in many cases a very heavy article, such as a wet blanket cannot be secured to 40 the line at all as its great weight will pull it out of the pin even when there is no breeze. To provide for an occasion of this kind, I have devised a clothes pin that the more strain put upon it, the tighter it will

50 hold, and having but a few parts that cannot be shaken loose, under ordinary conditions of wind and weather.

In a detailed description of my invention in which like characters of reference designate similar parts, wherever they occur in the views shown, 1 is a metal clothes line of

the usual kind, having different articles 2 and 3 retained thereon by clothes pins.

The clothes pin consists essentially of a support 4 preferably made of wood, and 60 substantially rectangular in facial contour. This support is provided at its opposite ends with openings 5 and 6, leading through the top and bottom faces of the support, and adapted to receive the vertical ends 7 and 8 65 of the clamping member. This clamping member may be made of any suitable material, but is preferably made of spring wire, and is adapted to be carried under the support and has the lowest point of its loop 9 70 substantially midway the length of the support. The clamping member is provided with the straight portions 10 and 11 adapted to bear against the bottom of the support, the purpose of which will hereafter be shown. 75 The ends 7 and 8 of the straight portions are bent upward, and terminate in the eyes 12 and 13, adapted to receive and slidingly fit the clothesline 1. These eyes have a diameter greater than the diameter of the 80 openings 5 and 6, in order that the eyes may be seated on the upper face of the support, and the support forced against the clothes line and the line consequently braced and prevented from bending or being formed 85 into kinks by the eyes under the weight of the clothes.

The straight portions 10 and 11 of the clamping member, when in normal position are held tightly against the bottom of the 90 wooden support by the loop 9, but will yield sufficiently to permit the corner of any article of apparel to be forced between them and the bottom of the support as shown in Fig. 1.

In applying the clothes pin to the line, the 95 line is made to enter the eyes 12 and 13 as shown in Fig. 2 and the eyes will be so in contact with the line as to hold the pin in whatever position it may be placed, but the pin is free to be slid to any desired point on 100 the clothes line.

From the foregoing description, taken in connection with the accompanying drawing, the construction and operation of my invention may be easily understood without a 105 more extended explanation.

Having thus described my invention, what I claim is:—

1. A clothes pin comprising a support disposed parallel to a clothes line, and a clamp- 110 ing member having terminal means for engaging a clothes line and holding said sup-

port thereto, said clamping member being adapted to bind a garment against the support.

2. A clothes pin comprising a support 5 adapted to be carried underneath and parallel to a clothes line, and a clamping member having terminal means for engaging a clothes line and holding said support thereon, intermediate portions adapted to clamp a 10 garment against the support, and a spring connecting the intermediate clamping portions free of the support.

3. A clothes pin comprising a support adapted to be carried underneath and parallel to a clothes line, and a clamping member having straight portions adapted to bear against the bottom of said support, said straight portions terminating in eyes encircling the clothes line, and a spring between 15 20 the straight portions holding them against the support.

4. A clothes pin comprising a support having openings adjacent its ends, said support adapted to be carried underneath and parallel to a clothes line, and a clamping member having straight portions adapted to bear against the bottom of the support, the outer ends of said straight portions being bent upward to pass through the openings in the support and terminating in eyes 30 adapted to bear against the upper surface of the support and hold the support on the clothes line, and a dependent spring loop connecting the inner ends of the straight portions.

In testimony that I claim the foregoing as my own, I have hereto affixed my signature in the presence of two witnesses.

ROBERT E. McCREARY.
